CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

MULTI-INDORSEMENT MECHANISM.

1,107,008.

Specification of Letters Patent. Patented Aug. 11, 1914.

Application filed May 9, 1913. Serial No. 766,525.

To all whom it may concern:

Be it known that I, CHARLES C. ABBOTT, a citizen of the United States, residing at Pittsfield, county of Berkshire, State of Massachusetts, have invented an Improvement in Multi-Indorsement Mechanism, of which the following is a specification.

This invention relates to mechanism of the general type shown and described in Letters Patent Nos. 1,054,074 and 1,054,075, granted to me Feb. 25, 1913. This mechanism is limited in its use to a condition in group voting in which the same person has been nominated or indorsed for an office in a group by two or more parties, and his name appears on a plurality of party tickets, *i.e.* in a plurality of party lines, and has for its object to render it impossible to cast more than one vote for such person no matter in how many office lines his name may appear or in what positions in the several lines.

The purpose and nature of the mechanism in question are fully set forth in my prior patents above referred to, but, briefly stated, said mechanism comprises one or more multi-indorsement strips adapted for use in connection with columns of voting members, locking dogs operated by the voting members and coöperating with the strips, and a secondary interlock or wedge system connecting the several strips where more than one are used. Operation of a voting member, through the locking dog associated therewith, causes slack to be taken up in the corresponding multi-indorsement strip, thereby preventing the operation of another voting member provided with a locking dog in the same column, and also, through the wedge system, locking the other strips and preventing the operation of a voting member provided with a locking dog in any other column. Of course where all of the voting members corresponding to the same candidate are arranged in a single column the wedge system is unnecessary, since the multi-indorsement strip alone prevents the operation of more than one member in the same column.

The present invention has for its objects to provide a construction in which loose parts are, as far as possible, eliminated; to provide an improved multi-indorsement strip composed of interchangeable units, each complete in itself, which units have

permanently associated therewith all of the parts necessary for coöperation with the voting members, and which can be assembled into a complete strip and thereafter placed in position in the machine, different units being employed in accordance with the requirements; and also to provide an improved secondary locking attachment or wedge system, for use in connection with the multi-indorsement strips, which is of simple and compact construction, efficient in operation, and capable of being easily and quickly applied, in assembled form, to the machine.

With these and other objects in view I have devised the novel mechanism which I will now describe, reference being had to the accompanying drawings forming a part of the specification and in which:

Figure 1 is an elevation, partly broken away, illustrating my novel mechanism as seen from the front of the machine. Fig. 2 is a side elevation as seen from the left in Fig. 1. Fig. 3 is a horizontal section on the line 3-3, Fig. 4. Fig. 4 is an enlarged front elevation of the wedge system or attachment. Figs. 5 and 6 are, respectively, an elevation and a horizontal section of one of the locking dogs detached. Fig. 7 is an enlarged side elevation of one of the locking units of the multi-indorsement strip. Fig. 8 is a section on the line 8-8, Fig. 7.

10 denotes the framework, 11 the shafts of voting members, 12 a voting member operating lever, and 14 a counter dog, all of which parts may be of any ordinary or preferred construction.

The multi-indorsement strips are composed of two types of interchangeable units, herein for convenience referred to as locking units 15 and connecting units 16. Each strip is assembled with a locking unit 15 corresponding to or adjacent each voting member representing a candidate who has been nominated or indorsed by a plurality of parties. The connecting units are employed to connect the locking units with one another and with the wedge system. The units 15 and 16 are all of equal length, being sufficiently longer than the distance between two of the voting member shafts in the same column to permit each unit to be connected with the next adjacent unit above or below it, so that one unit 15 or 16 is employed in each column to correspond to each party line.

Each of the locking units 15 is composed of an upper section 17, a lower section 18, and a locking dog 19. Each of the sections 17 and 18 is formed with an elongated opening 20 and is provided at its end with a cross piece 21 secured thereto by a flat rivet 22. The ends of the cross pieces 21 are bent inwardly to form undercut guideways 23 (see Fig. 8), and the edges of the sections 10 are beveled, as at 24, the beveled edges of each section sliding freely in the guideways of the other section. The rivets 22 are provided with heads 25 which engage longitudinal slots 26 and 29 in the sections 17 and 18, respectively, the head 25 of the rivet 22 carried by the upper section 17 engaging the slot 29 in the lower section 18, and vice versa. The locking dog 19 comprises an elongated plate of metal, rounded at the ends for smoothness in operation, and provided adjacent its center with a hub 27 received in the opening 20 of the section 17. The hub 27 is formed with a transverse non-circular opening adapted to receive and fit 25 the voting member shafts, said opening permitting a voting member shaft to be passed freely therethrough but preventing rotation of the locking dog on said shaft. The shafts are shown as provided with grooves on their 30 opposite sides, and the hub 27 of the locking dogs are formed with inwardly projecting lugs 28 which engage said grooves. The sections 17 and 18 and locking dog 19 of each unit are held permanently assembled 35 by the rivets 22, engagement of the beveled edges 24 of the sections 17 and 18 with the ways 23 holding said sections against separation, and engagement of the hub 27 of the locking dog 19 with the opening 20 in 40 the section 17 retaining said locking dog in place between the sections.

At points slightly above the lower ends of the slots 29 the sections 18 are bent inwardly or forwardly to form offset lower ends 30, as shown most clearly in Figs. 2 and 7. The amount of the offset is sufficient to compensate for the thickness of the cross pieces 21 and bring the ends 30 substantially beneath the center of the unit as a whole. The 50 upper ends of the sections 17 are bent inwardly or rearwardly to form hooks 31 provided with laterally extending lugs 32. Each hook 31 is adapted to engage a slot in the unit immediately above, and the lugs 32 55 retain said hook in engagement with said slot. The multi-indorsement strip shown at the left in Fig. 1 includes two adjacent locking units 15, and the hook 31 of the upper section 17 of the lower unit is engaged 60 with the slot 29 in the lower section 18 of the upper unit, thereby connecting said units. To disconnect the same after the strip has been removed from the machine 65 said units are turned out of alignment with one another, thereby permitting the lugs 32

to pass through the slot 29, said units being assembled in a similar manner, as will be obvious.

The connecting units 16 comprise single sections shown as flat plates or links provided with slots 34 and with elongated openings 33 through which the voting member shafts 11 pass freely. Said plates are formed with offset lower ends 35 to facilitate the connection thereof with adjacent units, and are provided at their upper ends with hooks 36 having laterally projecting lugs 37 similar to the hooks 31 and lugs 32 at the upper ends of the sections 17 of the locking units 15.

It will be understood that in arranging the machine a multi-indorsement strip composed of units 15 and 16 will be employed for each column containing one or more voting members corresponding to a candidate who has been nominated or indorsed by a plurality of parties, a locking section 15 being employed adjacent said voting member or members, and the remainder of the strip being composed of connecting units 16. The proper units are first assembled in the necessary arrangement, according to the requirements, to form a complete strip, and the strip in its completely assembled form is then applied to the machine. The units are connected to one another by the engagement of the hooks 31 or 36 with the slots 29 or 34 of the units immediately above, as the case may be, it being obvious that a locking unit may be substituted for a connecting unit at any point, and vice versa, as required. In applying the assembled strip to the machine the shafts 11 of the proper voting members are passed through the hubs 27 of the locking dogs 19, so that said dogs will turn with said shafts.

The secondary locking attachment or wedge system comprises a series of vertically sliding wedges 38, a set of laterally sliding outer plates 39 and a set of laterally sliding inner plates 40. The wedges are retained in place between the plates and said plates are held assembled by means of pins or rivets 41 and 43. The pins 41 pass through and are immovably secured to the plates 39 and slide in slots 42 in the plates 40. The pins 43 pass through and are immovably secured to the plates 40 and slide in slots 44 in the plates 39. The rivets 43 are preferably provided with washers 51. The series of wedges and plates forms an attachment complete in itself. The wedges 38 are formed with vertical slots 45 and the plates 39 and 40 with horizontal slots 46 which receive the voting member shafts 11 upon which said wedges and plates are supported and guided. The plates and wedges may be placed upon any line of voting members that may be necessary to meet the requirements of use.

The wedges 38 are preferably formed of sheet metal and are provided with upwardly extending stems 47. Said stems are formed with forwardly projecting lugs or wings 48, 5 which engage the upper edges of the plates 39 and 40 and limit the downward movement of the wedges, and at their upper ends with rearwardly turned hooks 49 similar to the hooks 31 and 36 and having laterally 10 projecting lugs 50 similar to the lugs 32 and 37. By means of the hooks 49 the wedges 38 are connected with the lowermost units of the multi-indorsement strips in precisely the same manner as that in which said units 15 are connected with each other. The inner plates 40 are rigidly connected in pairs at opposite sides of the wedges by the pins or rivets 43, and the outer plates 39 are similarly rigidly connected in pairs at opposite 20 sides of the plates 40 by the pins or rivets 41. The plates of the two sets are in staggered relationship to one another, the plates 39 breaking joints about midway of the plates 40, and vice versa. The pins 41 are 25 located adjacent the ends of the plates 39, and the pins 43 are similarly located adjacent the ends of the plates 40. The slots 42 and 44 in the plates 40 and 39, through which the pins 41 and 43 pass loosely, are, 30 in the case of the intermediate plates of the series, located at substantially the centers of said plates. At each end of the series is a pair of plates of one half the length of the other plates of the series, and the slots 42 and 44 thereof extend to the outer edges of 35 said plates. In a series comprising an odd number of wedges, as shown in the drawings, the short end plates at one end of the series form part of the set 39, and those at the opposite end form part of the set 40. Where an even number of wedges is employed the short plates at the opposite ends of the series will belong to the same set 39 or 40, as will be obvious. 40

45 The arrangement of the wedges, plates, and pins is such that normally, or when all of the wedges are in their lowermost positions, there is an amount of slack in the system sufficient to permit one of the wedges to 50 be moved upwardly into the position occupied by the central wedge as shown in Figs. 1 and 4. It will be observed that there is a pin 41 and a pin 43 adjacent each of the wedges 38 and lying on opposite sides thereof. When a wedge is moved upwardly, engagement thereof with the adjacent pins 41 and 43 causes said pins and the plates to which they are immovably secured to be moved in opposite directions away from one 55 another. The amount of movement of the plates 39 and 40 permitted by the pins 41 and 43 and slots 42 and 44 is just enough to permit one wedge only in the assemblage to be moved into its uppermost position. The 60 pins 41 and 43 at the left of an operated wedge closely engage the left sides of the wedges at the left, and the pins at the right of the operated wedge closely engage the right edges of the wedges at the right, thus locking all unoperated wedges against operation until the wedge which has been 65 raised is returned to normal position. 70

The complete operation of the mechanism is as follows. Fig. 1 shows portions of five party lines and five office columns to three 75 of which multi-indorsement strips have been applied. The party lines are counted from the top downward and the office columns from right to left, as seen in Fig. 1. This figure illustrates a condition in which the same candidate has been nominated or indorsed by the first, second, third and fourth parties, his name appearing in the fifth column in the first and second party lines, in the third column in the third party line, 80 and in the first column in the fourth party line. In other words, the fifth voting member in the first party line, the fifth voting member in the second party line, the third voting member in the third party line and the first voting member in the fourth party line all represent the same individual. In arranging or assembling the multi-indorsement strips a locking unit 15 is employed for each of these voting members, the balance of each strip being made up of connecting units 16 inasmuch as none of the other voting members in the several columns are affected by the multi-indorsement conditions. As shown in Fig. 1, the first strip is 85 composed of a single locking unit directly connected with the corresponding wedge 38, the second strip is composed of one locking unit 15 and one connecting unit 16 intermediate said locking unit and the corresponding wedge 38, while the third strip is composed of two locking units and two connecting units. Those columns in which the name of the candidate in question does not 90 appear are not provided with multi-indorsement strips, this being the case with respect to the second and fourth columns in the arrangement shown and the corresponding wedges 38 remain permanently in their normal or lowermost positions. Each of the multi-indorsement strips is connected at its lower end with a corresponding wedge 38 of the wedge system. Said wedge system or attachment is placed in position on the party line immediately below that of the lowermost party indorsing the candidate in question by slipping the same over the shafts or voting members in that line, said shafts passing through the slots 45 and 46 as above explained. 100

105 The heads 25 of the rivets 22 carried by the upper sections 17 of the locking units 15 normally lie in the upper ends of the slots 29 in the lower sections 18, so that upward movement of an upper section is transmitted 110

115

120

125

130

- to the corresponding lower section and is impossible without a corresponding upward movement of said lower section. In operating a voting member, or moving the same to voted position, the shaft thereof is given a quarter turn, more or less. When a voting member included in an assemblage (meaning voting members pertaining to any single candidate) is so operated the locking dog 19 thereon is turned from its normal horizontal position into an approximately vertical position. When so turned engagement of the dog with the cross-piece 21 immediately above the same causes said cross-piece and locking unit to be moved upward. Also, engagement of said operated dog with the cross-piece 21 immediately below the same locks said last named cross-piece and the upper section 17 of the corresponding unit against upward movement. Upward movement of the section 18, through the engagement with the slot 29 therein of the hook 31 or 36 of the unit below, causes the unit 25 below to be drawn upward also, the two sections of each locking unit moving upwardly together, and this upward movement being transmitted through all intervening units to the corresponding wedge 38 which is also drawn upwardly. Also, when a section 17 is locked by an operated locking dog against upward movement, engagement of the hook 31 thereof with the slot 29 of the lower section of a locking unit above locks said section and the corresponding sections of all superimposed locking units against upward movement, this locking action being transmitted through any connecting units which may intervene between the locking units. 35 The locking dogs above an operated dog will therefore closely engage the upper cross-pieces 21 of the corresponding locking units, which cannot move upward, and the locking dogs below the operated dog will closely engage the lower cross-pieces of the units, which cannot move downward, thus locking all other voting members of the assemblage in that column against operation. Moreover, since operation of a voting member in the assemblage raises all of that portion of the corresponding multi-indorsement strip which lies below said member together with the wedge 38 connected therewith, it being impossible to operate a voting member 50 in the assemblage without raising the corresponding wedge, and since the wedge system, as above explained, is so arranged as to permit only one of the wedges to occupy a raised position at one time, it follows that when one voting member of the assemblage in any one column has been operated, operation of another voting member of the assemblage in any other column is prevented. In Fig. 1, one voting member is shown 55 in the voted position, namely, that in the third line and the third column, and the wedge 38 corresponding to that column has been raised, thereby preventing movement of any other of the wedges and locking the voting members of the assemblage in the first and fifth columns against operation. The wedge attachment herein shown is adapted for use in connection with five or less office columns. It is necessary to employ a separate attachment for each assemblage, and preferably a plurality of these attachments will be provided for each machine, different attachments being of different sizes, i. e., including different numbers of wedges in order to accommodate the same 70 to varying requirements. 75 The voting member shafts 11 extend for a considerable distance beyond the framework, as shown in Fig. 2, so that two or more multi-indorsement strips may be employed for each column if required by the conditions, as explained in my prior patent No. 1,054,074, above referred to. Similarly two or more wedge attachments may be applied to the same office line if necessary, 80 these assembled attachments, as shown in Figs. 2 and 3, being relatively compact and flat and occupying relatively little space longitudinally of the shafts 11. 85 Having thus described my invention, I 90 claim: 95
  1. In a multi-indorsement strip for voting machines, a locking unit comprising a plurality of relatively sliding sections and a locking dog coöperating with said sections and permanently connected therewith. 100
  2. In a voting machine, a multi-indorsement strip composed of locking units and connecting units, said units being interchangeable in position and being provided with means for detachable connection with one another, and said locking units each comprising a plurality of relatively sliding sections and a locking dog coöperating with said sections and permanently connected therewith. 105
  3. In a multi-indorsement strip for voting machines, a locking unit comprising a pair of permanently connected, relatively sliding sections and a locking dog, said sections and dog being provided with coöperating means for permanently retaining said dog between said sections. 115
  4. In a voting machine, the combination with voting members having shafts, of a multi-indorsement strip including one or more locking units each comprising a pair of permanently connected, relatively sliding sections having openings and a locking dog between said sections and having a hub received in one of said openings, said hub having a transverse opening adapted to receive and fit the corresponding voting member shaft. 120
  5. In a voting machine, the combination 130

- with voting members arranged in a column and having shafts, of a multi-indorsement strip composed of locking units and connecting units, said units being interchangeable in position and being provided with means for detachable connection with one another, and said locking units each comprising a pair of permanently connected, relatively sliding sections having openings and 5 a locking dog between said sections and having a hub received in one of said openings, said hub having a transverse opening adapted to receive and fit the corresponding voting member shaft.
- 10 6. In a voting machine, a multi-indorsement strip composed of a plurality of units including one or more locking units, each of said locking units comprising upper and lower sections having means for slidably connecting the same, said lower section having a slot and said upper section having a hook adapted to engage the slot in the lower section of a unit above.
- 15 7. In a voting machine, a multi-indorsement strip composed of a plurality of units including one or more locking units, each of said locking units comprising upper and lower sections having means for slidably connecting the same and a locking dog 20 operating with said sections and permanently connected therewith, said lower section having a slot and said upper section having a hook adapted to engage the slot in the lower section of a unit above.
- 25 8. In a voting machine, a multi-indorsement strip composed of a plurality of units including one or more locking units, each of said locking units comprising upper and lower sections having means for slidably connecting the same, said lower section having a slot, and said upper section having means engaging said slot and a hook adapted to engage the slot in the lower section of a unit above.
- 30 9. In a multi-indorsement strip for voting machines, a locking unit comprising upper and lower sections having slots, a cross piece carried by each of said sections and having a guideway in which the other section slides, and a rivet securing each of said cross pieces to the corresponding section and having a head received in the slot of the other section.
- 35 10. In a voting machine, the combination 55 with voting members having shafts, of a multi-indorsement strip including one or more locking units each comprising upper and lower sections having openings and slots, a cross piece carried by each of said sections and having a guideway in which the other section slides and is permanently retained, a rivet securing each of said cross pieces to the corresponding section and having a head received in the slot of the other section, said upper section having a hook
- adapted to engage the slot in the lower section of the unit above, and a locking dog between said sections and having a hub received in one of the openings therein, said hub having a transverse opening adapted to receive and fit the corresponding voting member shaft.
- 40 11. In a voting machine, a multi-indorsement strip composed of a plurality of units including one or more locking units, each of said locking units comprising upper and lower sections having means for slidably connecting the same, said lower section having a slot, and said upper section having a hook provided with laterally extending lugs 45 and adapted to engage the slot in the lower section of a unit above.
- 45 12. In a voting machine having voting members, a multi-indorsement strip composed of locking units and connecting units 50 interchangeable in position, said locking units having slots and being adapted to cooperate with said voting members, and said connecting units being inactive with respect to said voting members and each comprising a single section provided at its lower end with a slot and at its upper end with a hook adapted to engage the slot in a unit above.
- 55 13. In a voting machine, a multi-indorsement strip composed of locking units and connecting units, said units being interchangeable in position and of equal length, said locking units each comprising upper and lower sections having means for slidably connecting the same, the lower sections of 60 said locking units having slots and the upper sections thereof having hooks to engage the slots in the units above, and said connecting units each comprising a single section provided at its lower end with a slot similar to the slots in the lower sections of the locking units and at its upper end with a hook similar to the hooks of the upper sections of said locking units.
- 65 14. In a voting machine, the combination 65 with voting members having shafts, of a multi-indorsement strip composed of locking units and connecting units, said locking units having slots and being adapted to cooperate with said voting members and said connecting units being inactive with respect to said voting members and each comprising a single plate having an elongated opening through which the corresponding voting member shaft passes freely, said plate being provided at its lower end with a slot and at its upper end with a hook adapted to engage the slot in a unit above.
- 70 15. In a voting machine, the combination 70 with voting members having shafts, of a multi-indorsement strip composed of interchangeable locking units and connecting units, each of said locking units comprising upper and lower sections having openings and slots, a cross piece carried by each of 75

- 6
- said sections and having a guideway in which the other section slides and is permanently retained, a rivet securing each of said cross pieces to the corresponding section and having a head received in the slot of the other section, said upper section having a hook provided with laterally extending lugs and adapted to engage the slot in the lower section of the unit above, and a locking dog between said sections and having a hub received in the openings therein, said hub having a transverse opening adapted to receive and fit the corresponding voting member shaft; and said connecting units 10 each comprising a single plate having an elongated opening through which the corresponding voting member shaft passes freely, said plate being provided at its lower end with a slot similar to the slots in the lower section of the locking units and at its upper end with a hook similar to the hook of the upper sections of said locking units.
16. In a voting machine, the combination with voting members arranged in lines, of 15 a multi-indorsement strip composed of a plurality of detachably connected locking units and connecting units, each complete in itself and each of a length substantially equal to the distance between the lines of 20 voting members, said locking units being adapted to coöperate with said voting members, and said connecting units being inactive with respect to said voting members.
17. In a voting machine, in combination, 25 a series of multi-indorsement strips each composed of interchangeable locking units and connecting units of equal length, and a series of wedges corresponding respectively to the several strips, said locking units each 30 comprising relatively sliding upper and lower sections and said connecting units each comprising a single section, said connecting units and the lower section of said locking units having similar slots, and said 35 wedges, connecting units, and the upper sections of said locking units having hooks adapted to engage the slots in units above, whereby said units may be detachably connected with said wedges and with each other.
- 40 18. In a multi-indorsement mechanism for voting machines, a wedge system comprising a series of vertically movable wedges and a series of laterally sliding plates, said plates being moved by an operated wedge 45 to lock all of the other wedges in the series, and said wedges being provided with means to engage said plates and limit the downward movement of said wedges.
- 50 19. In a multi-indorsement mechanism for voting machines, a wedge system comprising a series of vertically movable wedges and a series of laterally sliding plates, said plates being moved by an operated wedge 55 to lock all of the other wedges of the series, and said wedges having upwardly project-
- ing stems provided with projecting lugs to engage the edges of said plates and limit the downward movement of said wedges.
20. In a voting machine, in combination, a series of multi-indorsement strips, a series 70 of vertically movable wedges corresponding respectively to the several strips, and a series of laterally sliding plates, said plates being moved by an operated wedge to lock all of the other wedges in the series, and 75 said wedges having upwardly projecting stems provided with means for attachment to said strips and with means to engage said plates and limit the movement of said wedges.
21. In a multi-indorsement mechanism for voting machines, a wedge system comprising a series of vertically movable wedges, a set of laterally sliding inner plates, a set of laterally sliding outer plates, and means 80 connecting said plates and engaged by said wedges whereby said plates are moved by an operated wedge to lock all of the other wedges of the series.
22. In a multi-indorsement mechanism for voting machines, a wedge system comprising a series of vertically movable wedges, a set of laterally sliding inner plates, a set of laterally sliding outer plates overlapping said inner plates, and pins connecting said plates 85 and engaged by said wedges whereby said plates are moved by an operated wedge to lock all of the other wedges of the series.
23. In a multi-indorsement mechanism for voting machines, a wedge system comprising 90 a series of vertically movable wedges, a set of laterally sliding inner plates, a set of laterally sliding outer plates arranged in pairs at opposite sides of said wedges, a set of laterally sliding outer plates arranged in pairs at opposite sides of said inner plates, 95 all of said plates having slots, pins immovably connecting the inner plates of each pair and sliding in the slots in the outer plates, and pins immovably connecting the outer plates of each pair and sliding in the slots of the inner plates, said pins being engaged by said wedges and moved by an operated wedge to move said plates and lock all of the other wedges in the series.
24. In a voting machine, in combination, 100 voting members having shafts, a series of multi-indorsement strips, a series of vertically movable wedges connected respectively with the several strips and having vertical slots to receive the voting member shafts, 105 and a series of laterally sliding plates having horizontal slots to receive said voting member shafts, said plates being moved by an operated wedge to lock all of the other wedges in the series.
25. In a voting machine, the combination 110 with voting members arranged in a column, of a multi-indorsement strip connecting said voting members and composed of locking units and connecting units collectively equal 115

in number to the connected voting members in the column, said units being interchangeable in position and being provided with means for detachable connection with one another, and said locking units each comprising a plurality of relatively sliding sections and a locking dog coöperating with said sections and permanently connected therewith.

10 26. In a voting machine, a multi-indorsement strip composed of locking units and connecting units, said units being interchangeable in position and being provided with means for detachable connection with one another, said connecting units each comprising a single section, and said locking units each comprising a plurality of relatively movable sections.

27. In a voting machine, the combination 20 with voting members arranged in a column, of a multi-indorsement strip connecting said voting members and composed of locking units and connecting units collectively equal in number to the connected voting members 25 in the column, said units being interchangeable

able in position and being provided with means for detachable connection with one another, said connecting units each comprising a single section inactive with respect to said voting members, and said locking units each comprising a plurality of relatively movable sections.

28. In a voting machine, the combination with voting members arranged in lines, of a multi-indorsement strip composed of a plurality of locking and connecting units corresponding in number to the lines of voting members, each of said units being complete in itself and each being provided with means for detachable connection with adjacent units, said locking units being adapted to co-operate with said voting members, and said connecting units being inactive with respect to said voting members.

In testimony whereof I affix my signature 45 in presence of two witnesses.

CHARLES C. ABBOTT.
